FUEL SUPPLYING MEANS USING CRANK-CASE PRESSURE DEVELOPED IN A TWO-CYCLE ENGINE FOR DELIVERING FUEL TO THE CARBURETOR

Warren C. Conover, Waukegan, Ill., assignor to Outboard, Marine & Manufacturing Company, Waukegan, Ill., a corporation of Delaware

Application October 1, 1949, Serial No. 119,085

18 Claims. (Cl. 123—139)

1

This invention relates to a fuel supplying means using crank case pressure developed in a two-cycle engine for delivering fuel to the carburetor of such engine.

Cross reference is made to my co-pending applications Serial No. 276,021 and Serial No. 276,022, filed March 11, 1952.

It has been the general practice in the outboard motor industry to make the fuel tank a unitary part of the power head structure. Size and weight limitations have made it necessary that the tank have limited fuel capacity, thus requiring relatively frequent filling, an operation which, in rough water, frequently involves the spilling of fuel, the fouling of the fuel tank and much inherent waste and danger. It is, therefore, the major object of the present invention to provide a fuel tank which will be separate from the power head and, although connected therewith for use, may be readily separated from the power head for independent transportation. In providing such a fuel tank, the weight of the outboard motor as such is greatly reduced, thus facilitating transportation and mounting and dismounting; the size of the fuel tank may be greatly increased, thus minimizing fuel replacement on the open water; the introduction of foreign matter into the fuel tank is made unlikely; and the spilling and fire hazard is virtually eliminated.

In order to make the fuel feed automatically from a remote fuel tank to the prime mover of the outboard motor, the present invention makes use of the fact that the engines ordinarily powering outboard motors are two-cycle engines in which the combustible mixture is compressed in the crank case preliminary to its delivery to the combustion chamber in the cylinder. It is an object of this invention to provide means for the controlled delivery of crank case compression to the surface of the fuel in the remote tank thereby creating a pressure differential sufficient to cause the fuel to flow from the remote tank to the carburetor of the engine for use.

In order effectively to accomplish the aforesaid objectives, it is a further purpose of the present invention to provide a novel and improved organization of the crank case, the carburetor and valve controlled connections to the remote fuel tank.

Still other objects of the invention will appear more fully from the following disclosure, having reference to the accompanying drawings, in which:

Fig. 1 is a view in perspective of a remote fuel tank used for the purposes of the present invention.

tion, portions of the associated engine and carburetor being diagrammatically illustrated, partially in side elevation and partially in section.

Fig. 2 is a greatly enlarged fragmentary detail view in perspective of the fuel tank shown in Fig. 1, portions thereof being broken away to expose the interior construction.

Fig. 3 is a fragmentary detail view in axial section of a priming pump incorporated in the fuel tank.

Fig. 4 is a bottom plan view of the pump shown in Fig. 3.

Fig. 5 is a view partially in perspective and partially in transverse section showing a mounting arrangement for the priming pump and fuel and pressure supply connections from and to the fuel tank.

Fig. 6 is a view in side elevation of component crank case, valve plate and carburetor parts as they appear when separated.

Fig. 7 is a detail view taken in section on an enlarged scale on the plane indicated at 7—7 in Fig. 6.

Fig. 8 is a view taken in longitudinal section through the separable communication line coupling on the axis of one of the communication conduits.

Fig. 9 is a view taken in transverse section on the line 9—9 of Fig. 8.

Fig. 10 is a detail view of one of the coupling elements in side elevation with portions thereof broken away to an axial section to show the seating of a check valve thereof.

Fig. 11 is a view in perspective diagrammatically illustrating in position on a boat an outboard motor equipped with the present invention, the communication coupling between the motor and fuel tank having been broken.

Fig. 1 diagrammatically illustrates how the invention operates. The two-cycle engine 15, here shown as having two alternately firing cylinders 16, 17, and separate crank cases 18 and 19, respectively, in which the combustible mixture is compressed for delivery to the cylinders in the usual manner, has a carburetor 20 with float chamber 21 to which a pipe 22 leads from the coupling element 23 which is desirably attached by bracket 24 to the engine. The complementary coupling element 25, detachably engaged with coupling element 23, provides an extension 26 of pipe 22 which is connected by hose 27 with the fuel supply tank 30 in a manner hereinafter to be described.

In order to supply pressure to the fuel tank 30 for the delivery of fuel therefrom through hose

27 and pipe 22 to the carburetor, a check valve arrangement allows pressure to be communicated from the respective crank cases to a pressure chamber 31 mounted on the engine and communicating through pipe 32, coupling elements 23 and 25, extension pipe 33 and hose 34 with the fuel tank 30.

The fuel tank 30 is shown in detail in Fig. 2 and parts thereof are separately illustrated in Figs. 3 to 5. The tank comprises side wall portions 35, a bottom 36 and a top 37. The latter is positioned materially below the top of the side wall portions 35, the side wall portions overhanging at 38 to provide a recess clearly shown in Figs. 1 and 2 in which the dual hoses 27 and 34 are conveniently coiled when not in actual use. The top of the tank is desirably drained by ports 16 shown in Fig. 1 and Fig. 2, these being located at the ends only to drain off water or fuel spillage without soiling the sides, which in carrying, may contact the operator's clothing. These hoses, incidentally, are desirably united by unitarily molding their rubber or synthetic rubber jackets together throughout the greater portions of the hose lengths, separating the respective hoses only at their ends where they are attached to their respective couplings.

Fixed in the top wall is any suitable filling cap, the particular arrangement shown comprising a sleeve 39 mounted in the top wall and threaded to receive the cap 40 which, as best shown in Fig. 1, may be flanged for convenient manipulation.

Separately prefabricated and mounted in the top wall for unitary assembly with the tank is a plate 41 which carries a gage mechanism 42 of conventional construction, the pump 43, and hose connections and valving arrangements now to be described.

The pump is used solely for priming or filling the carburetor bowl with sufficient fuel to initiate engine operation and thereby to develop the pressure in the fuel tank for further deliveries of fuel for continued engine operation.

It is convenient to use a diaphragm pump for this purpose. The pump casing 44 (Fig. 3) comprises upper and lower complementary parts 45, 46 which are bolted together upon a diaphragm 47, which also serves as a gasket. The parts 45 and 46 have complementary cavities which provide a valve chamber 48, a pump chamber 49 and a valve chamber 50. The part 46 provides valve seats 51 and 52 for the valves 53, 54, which operate in the valve chambers 48 and 50, respectively. The opening through the valve seat 51 communicates with an inlet chamber 55, which is also formed as a cavity in the casing member 46. Access of the fuel to this chamber is permitted through a screen 56 which closes the bottom of the cavity.

The entire casing 44 is rigidly mounted by a tube 43 from the plate 41. Through this tube extends the pump operating plunger 57, the handle 58 of which is exposed for manipulation by the operator. At its lower end, the plunger 57 is conventionally connected with the diaphragm and is normally biased toward the upward position in which it is shown in Fig. 3 by a compression spring 59 pocketed in the lower casing member 46 and acting upwardly upon the diaphragm. A port at 60 leads from the valve chamber 48 to the pump chamber 49 and a port 61 leads from the pump chamber to a conduit 62 which opens through the valve seat 52 into valve chamber 50. From this point, a pipe 63 leads upwardly and, subject to control by a manually operable valve

64, this pipe communicates with the fuel line 34 as shown in Fig. 5.

Manipulation of the pump plunger draws fuel through the screen into chamber 55 and thence past the valve seat 51 and check valve 53 into chamber 48, from which the fuel flows through port 60 to the pump chamber 49 beneath the diaphragm. As the diaphragm is pushed downwardly by the plunger, it displaces the fuel from the pump chamber 49, check valve 53 being closed and check valve 54 open, whereby the fuel passes through duct 61 and conduit 62 past the seat 52, check valve 54 to the fuel delivery pipe 63 and thence through the fuel line 34 to the carburetor bowl. The construction is such that when the engine is running and the tank is subjected to pressure in the manner hereinafter described, the pressure differential between the tank and the carburetor bowl causes the fuel to flow on identically the same path, opening the check valves 53 and 54 and passing through pipe 63 and fuel hose 34 to the carburetor independently of pump operation.

The arrangement best shown in Figs. 6 and 7 (cf. Fig. 1) greatly facilitates the making of the various connections to the engine proper. Fig. 6 shows the actual preferred construction, whereas Fig. 1 is diagrammatic.

Although the cylinders 16 and 17 happen to be vertically superimposed in the engine chosen for exemplification, the ports 65, 66 which communicate with the respective crank cases 18 and 19 are disposed on an oblique line for convenience of assembly. These ports are the fuel mixture inlet ports. These ports are respectively encircled by the gasket 67 which has openings registering with the ports and is also provided with openings 68 and 69 to which, respectively, ducts 70 and 71 lead from the respective crank cases.

Over the gasket 67 is applied the valve plate 75, also shown in Fig. 6 and Fig. 7. This plate is laid over the gasket without inversion from the position of Fig. 6, its valve ports 76 and 77 being respectively in communication with the gasket openings 68 and 69 at points relatively remote from the ducts 70 and 71, as best shown in Fig. 1. A single piece of rubber, reenforced by a flat spring 78, the spring and the rubber both being anchored by central bolts at 79, provides flap type check valves 80 and 81, respectively, which cover the valve ports 76 and 77. Since the respective crank cases are alternately subject to compression, and since the valves 80 and 81 open outwardly in response to crank case compression, it will be evident that these valves will open alternately to communicate crank case compression to the common pressure chamber 31 previously described. This pressure chamber may desirably constitute a cavity in the carburetor mounting plate 83 which, in Fig. 6, is shown in its inverted position after removal from plate 75.

The same mounting plate 83 has cavities 84 and 85 with which the mixture port 86 from the carburetor communicates. The respective chambers 84 and 85 overlie, respectively, annular series of ports 87 and 88 in the valve plate 75 for the controlled admission of mixture into the respective crank cases. The cavities 84 and 85 in the carburetor mounting plate 83 do not need to correspond in cross section with the ports 65 and 66 in the crank case because there is an intervening gasket 90 which has openings at 91 and 92 sufficiently large to provide communication to all of the ports 87 and 88 respectively.

Behind plate 75, and disposed in the openings

65 and 66 of the motor block, are special mixture inlet check valves 89 which are shown only in dotted lines in the drawing of the valve plate 75 in Fig. 6, but are more particularly described in a companion application. Any conventional check valve will suffice, so far as the disclosure of the present invention is concerned.

Thus air admitted through the carburetor 25, in the usual manner, is carbureted from fuel supplied to the carburetor bowl 21 through the fuel hose 34 from tank 30, such fuel being either pumped to the bowl or delivered to it by pressure which is communicated to the tank from the engine crank case or crank cases. The carbureted air enters the engine in any suitable manner, the two-cycle engine exemplifying the invention being supplied with mixture through its crank cases, as is usual. The flap valves 89 open to admit the air when the piston is moving outwardly in a given crank case and close as the piston returns, whereby pressure is created in the crank case. The transfer ports for delivering the compressed mixture from the crank case to the combustion chamber are not shown, having no relation to the present invention, and being conventional.

However, when any given crank case in a device embodying the invention is under compression, and until the tank 30 reaches equal pressure, a portion of the mixture from the crank 30 case will escape through the check valve 80 or 81 to the pressure chamber 31 from which pressure will be communicated as previously explained to the fuel tank 30 for maintaining a pressure differential which will effect continued delivery 35 of fuel to the carburetor.

In the device disclosed, any blow back of flame is virtually impossible but, as a precaution, to prevent flame from being propagated from either crank case to the tank 30, the pressure communication system includes the extremely flat, thin chambers 68 and 89 formed in the gasket 67, which provides parallel metal walls in close proximity to each other. In such a device, flame propagation is impossible because the metal will necessarily cool burning gases below the combustion point.

The device is fully operative regardless of any quickly separable connection in lines 27 and 34. However, in order to effectuate fully the objectives of the present invention, it is desirable to provide for ready connection and disconnection of such lines to the engines, and to this end coupling elements 23 and 25 are employed. Reference has already been made to them. The preferred construction will now be described in detail.

The connector element 23, mounted on bracket 24, may comprise simply a block 95 in which are mounted the male connector studs 96 and 97, stud 96 being typical and shown in section in Fig. 8. Each stud is tubular and provided with a nipple at 94 for the appropriate hose connection. Each stud is desirably closed at its outer end 98 except for a delivery port or ports at 99 which are so oriented respecting the outboard motor that any fuel remaining under residual pressure when the connector elements are separated will be discharged laterally, preferably sideward and downwardly outside the stern of a boat as indicated by the arrows in Fig. 11. The two ducts shown in Figs. 8 and 11 discharge sideward and downwardly respectively.

In addition to the male connector studs 96 and 97, the mounting block 95 carries a dowel 100 75

which is desirably provided with a pointed and shouldered head 101 with which engages the manually releasable detent 102 pivoted to connector element 25. The latter connecting element comprises a pair of chambers 103, 104, views in section through chamber 103 being shown in Figs. 8 and 10. Each chamber is provided with its own separate nipple 107 for the respective hose connection, the nipple being screwed into the appropriate tube which projects from the rear of the chamber.

At the outer end of the chamber, there is an annular receiver 108 which is interiorly recessed to provide a suitable female seal, which may comprise the O-ring 109. When the coupling elements are engaged, the appropriate male plug, such as plug 96, is received through the annular receiver 108 and is sealed by the O-ring. The closed end portion 98 of the plug, upon entering the receiver, thrusts aside the valve 110 and extends sufficiently past washer 111 so that the ports 99 communicate with the interior of chamber 98. The valve 110 is mounted on a guide 113 which, as best shown in Fig. 9, is of polygonal cross section to permit free flow around the guide. The guide member is socketed to receive the compression spring 112 which normally urges the guide toward the position shown in Fig. 10, wherein the valve 110 is seated within the O-ring seal 109. Upon withdrawal of the male plug, the valve immediately seats itself to seal the appropriate hose from communication with the atmosphere. In the duplex connectors shown, the two hoses which lead to and from tank 30 are sealed simultaneously. They are also simultaneously placed in communication with the pressure and fuel delivery pipes 32 and 22 when the connector elements are reassembled, the detent 102 automatically holding the connector elements in mutually assembled engagement until manually released.

In the use of the device, it will be apparent that no greater pressures can ever be established in the tank 30 than are developed in the crank cases 18 and 19. In the case of repeated crank case combustion sometimes occurring due to faulty carburetor adjustment or ignition faults, pressures may become excessive. Therefore, to safeguard the tank against undue pressure increases, I provide a suitable safety valve which, in the device shown, comprises a disk 115 of any suitable material such as synthetic rubber, which is normally held by a compression spring 116 and metal washer 117 against a seat at 118 around the vent aperture 119 in the mounting plate 41. The spring chamber is desirably vented laterally through port 120 (Fig. 5) so that in the event that there should be any discharge from the tank, the force thereof will be expended harmlessly within the overhanging top flange 38 within which the duplex hose is usually coiled when not in use.

Fig. 11 illustrates, somewhat conventionally, an outboard motor structure with the duplex hose in process of application thereto. When the connectors are secured together to complete the pressure and fuel supply connections between the tank and the outboard motor, a few strokes of the pump will deliver a sufficient quantity of fuel into the carburetor bowl to enable the outboard motor engine to be started. As soon as such engine is started, and even during the preliminary cranking thereof, pressure will be communicated from the crank case or crank cases to the tank to establish a pressure differential which will

continue to deliver fuel through the check valves of the pump and the intervening hose to the carburetor bowl. When the use of the outboard motor is terminated, and particularly if it is desired to remove the motor from the boat for transportation, the connector elements are separated, whereby any pressure remaining in the tank is sealed therein. No seal is required for those connector parts which are attached to the motor because these are extremely short and the escape of a drop or two of liquid will release any pressure residual therein. The free ends of the hoses are now coiled in the channel provided at the top of the fuel tank and the fuel tank may thereupon be transported independently of the rest of the outboard motor structure.

The manufacture of the device is greatly simplified by reason of the fact that the pressure and fuel delivery terminals of the hoses are, at each end, comprised in prefabricated units which are capable of independent handling. Thus, at the upper end, the hoses connect to the mounting plate 83 which not only carries the carburetor but also provides communication with the crank case for the pressure line. At the lower end, the hoses connect to the mounting plate 41 upon which all parts extending into the tank are unitarily assembled.

I claim:

1. The combination with a two-cycle engine having a crank case in which pressure and vacuum are alternately developed as an incident to engine operation, of a remote fuel tank, a supply pipe from the tank to the engine and a pressure communicating conduit having a control valve and leading from said crank case to said tank for communicating to the tank pressure developed in said crank case, said control valve constituting means for closing said conduit when the crank case is under vacuum whereby the tank is continuously under pressure.

2. The combination with a two-cycle engine having a combustion cylinder and a separate mixture compression chamber, a carburetor, and a crank and piston for periodically compressing mixture in said chamber, of a remote and separate tank, a fuel delivery line from said tank to the carburetor having a flexible portion, and a pressure line from the chamber to the tank having a flexible portion and provided with a check valve opening outwardly of said chamber in said line for affording the communication of super-atmospheric pressure from said chamber to said tank when the pressure developed in the chamber exceeds that of the tank.

3. The combination with a two-cycle engine having an intermittent mixture compression and decompression in the crank case, of a remote tank and a pressure line from the crank case to the tank provided with a valve chamber and a check valve opening outwardly from the crank case in the path of flow of mixture from the crank case toward the tank whereby said pressure line is in communication with the crank case only during mixture compression.

4. The device of claim 3 in which said line includes a hose and a pair of separable connector elements, one of which is attached to the hose.

5. The device of claim 4 in which one of said elements comprises a male plug and the other an annular receiver having O-ring packing through which the plug is insertable, the element provided with the receiver also having a valve plug engageable in the O-ring packing alternatively with the male plug and biased toward such engagement, the valve plug being in the

path of introduction of the male plug to be disengaged from the O-ring packing upon insertion of the male plug.

6. In an outboard motor device, the combination with an outboard motor comprising a two-cycle engine having intermittent mixture compression in its crank case and provided with a carburetor for the production of such mixture, a remote and separately portable fuel tank at a level lower than said carburetor and provided with a sealed closure, a fuel line from said tank to the carburetor, and a pressure line from the crank case to the tank, said pressure line being provided with a controlling valve opening for the communication of maximum crank case pressure to said tank and having means for closing it when the crank case pressure interval has passed.

7. The device of claim 6 in which the respective lines have separable connectors, whereby the tank may be wholly disassociated from the outboard motor engine.

8. The device of claim 7 in which said connectors are dual, one such connector comprising a male plug for each of said lines and the other such connector providing receivers for the respective plugs.

9. The device of claim 8 in which the connector element having the receivers has O-rings constituting seals for the respective receivers and into which the respective male plugs are insertable.

10. The device of claim 9 in which the connector having the said receivers is further provided with valve plugs normally engaged in the respective O-rings and biased toward such engagement, the said valve plugs being in the path of the male plugs aforesaid to be displaced from the O-rings when the male plugs are inserted therein.

11. The device of claim 10 in which one of the said connectors is provided with a detent movably mounted thereon and provided with a handle for its manipulation, the other of said connectors having a latch device with which said detent is normally engaged in the assembly of said connectors.

12. In a device of the character described, the combination with a two-cycle internal combustion engine having periodic mixture compression in its crank case and provided with a carburetor for mixture formation, of a fuel tank, fuel and pressure lines communicating with the tank and respectively communicating with the carburetor and the crank case and unitary mounting plates on the engine and the tank respectively, each of said mounting plates being provided with terminal connections for both lines.

13. The device of claim 12 wherein the mounting plate on the engine carries said carburetor and provides mixture delivery ports leading from the carburetor to the engine, and other ports leading from the engine crank case to the pressure line.

14. The device of claim 13 in which a valve plate intervenes between the mounting plate and the engine and is provided with mixture and pressure ports and has inwardly opening mixture controlling check valve means regulating flow through the mixture ports and outwardly opening pressure controlling check valve means controlling mixture communication from the crank case to the tank.

15. The combination with a two-cycle internal combustion engine having periodic mixture compression in its crank case and provided with a carburetor for mixture formation, of a fuel tank,

a pressure communicating line from the engine crank case to the fuel tank and a fuel return line from the fuel tank to the carburetor, the latter line comprising a pump chamber, receiving and delivery check valves at opposite sides of the pump chamber, and a displacement member manually operable in the pump chamber for fuel delivery from the tank to the carburetor pending development of pressure in said tank, fuel flow after tank pressure is developed occurring through said pump chamber and valves.

16. In a two-cycle internal combustion engine having a pair of separate crank cases provided with adjacent ports and separate ducts, a gasket applicable to the crank cases and providing separate pressure chambers with which such ducts communicate, a valve plate having ports registering with the crank case ports and pressure chambers and provided with inwardly opening valves for the crank case ports and outwardly opening valves leading from the pressure chamber, a mounting plate having chambers communicating with all of said valves, a carburetor having mixture forming passages communicating through the mounting plate with the inwardly opening valves aforesaid, and a pressure line having communication through the mounting plate to the outwardly opening valves aforesaid.

17. The combination with a two-cycle internal combustion engine having a crank case, a crank and piston for intermittently compressing mixture in the crank case and a carburetor for form-

ing such mixture, the crank case having mixture inlet and outlet ports, a valve plate mounted on the crank case and having mixture inlet and mixture outlet valves controlling flow through the respective inlet and outlet ports of the crank case, and a mounting plate covering the valve plate and having mixture inlet and outlet passages communicating through the respective valves with the respective crank case ports, the carburetor being attached to the mounting plate in operative position to the mixture inlet ports, and a pressure supply line attached to the mounting plate and in operative connection therethrough with the mixture outlet port.

18. In an outboard motor having a remote fuel tank and a line leading thereto, the combination of said line with male and female connectors, the former comprising a plug in fixed connection with the outboard motor and having a lateral delivery port.

WARREN C. CONOVER.
